RIDGE VENTILATOR

James H. McDerment, Cleveland, Ohio, assignor
to The Swartwout Company, Cleveland, Ohio,
a corporation of Ohio

Application May 24, 1934, Serial No. 727,306

7 Claims. (Cl. 98—42)

This invention relates to a ventilator and particularly to one which is adapted to be used in connection with a roof and to extend there along for considerable distances, affording maximum ventilation and at the same time preventing access of rain to the interior of the building.

The objects of the invention are to provide improved structure of supports, baffle mounting means, and control means. A more specific object is the provision of improved means for supporting and anchoring the baffles, which will render them more readily attachable while making superior provision for drainage.

A further object is to provide a novel and improved controlling means for the damper which in accordance with its position closes the opening in the roof or opens the same.

Other and more limited objects will become apparent from the following description when read in connection with the accompanying drawings in which Fig. 1 is a transverse section corresponding substantially to the line 1—1 of Fig. 2; Fig. 2 is a central longitudinal section of a fragment of a ventilator having parts broken away and parts left in elevation; Fig. 3 is a detail section on the line 3—3 of Fig. 2; Fig. 4 is a detail section taken on the line 4—4 of Fig. 1; Fig. 5 is a detail in perspective showing an upper corner of one of the baffles; Figs. 6 and 7 are fragmentary views corresponding substantially to the upper right hand corner of Fig. 2 but showing the parts in different positions; Fig. 8 is a transverse section similar to Fig. 1 but showing the modified embodiment of my invention; Fig. 9 is a fragmentary detail elevation of a portion of the lower edge of one of the baffles; Fig. 10 is a section on the line 10—10 of Fig. 9; Fig. 11 is a section on the line 11—11 of Fig. 9 and Fig. 12 is a longitudinal sectional view similar to Fig. 2 but showing the modified form of Fig. 8.

Referring now to the embodiment of Figs. 1 to 7, the numerals 10 and 11 indicate, generally and schematically, spaced portions of a roof defining a ventilation opening therebetween. Secured to the members 10 and 11 are sheet metal plates or strips 12 and 13 which extend upwardly above the said roof sections and terminate in beads 14 and 15. Extending across the space between the members 12 and 13 adjacent the top thereof are a plurality of connecting strips 16. At similar spaced intervals are supporting bows indicated generally by the numeral 17 and comprising roof strip engaging portions 18 and 19 terminating at their lower ends in vertically upwardly extending projections 20 and 21, vertical support-

ing portions 22 and 23, upper angles 24 and 25 and a transverse top portion 26. Extending through the portion 18, the plate 12, and the downwardly bent end of the strip 16 is a connecting bolt or rivet 27. Similarly connecting elements 19, 13, and 16 is a connecting bolt 28.

A ridge roll 29 is supported on the upper angles 24 and 25 of the bows 17 to which it is connected by bolts or rivets 30 and 31 which also serve for the attachment of upper baffle supports 32 and 33. Each of the supports 32 and 33 extends outwardly and upwardly at substantially right angles to the angles 24 and 25 and terminates in sharply bent upwardly and backwardly bent, hook-shaped terminal portions 34 and 35. Baffles 36 and 37 are supported by the lower members 20 and 21 and the upper members 34 and 35 respectively, having lower struck-out loops 38 and 39 adapted to receive the members 20 and 21 respectively and having their upper edges inwardly and backwardly bent to hook shaped cross section and provided with openings 40 adapted to receive the elements 34 and 35.

Mounted upon a pair of adjacent bow members 17 and extending longitudinally of the device are spaced angle members 41 and 42 to which are secured the lower outwardly extending flanges 43 and 44 of vertical plates 45 and 46. Mounted for free rotation between the plates 45 and 46 are upper and lower pulleys 47 and 48. Registering vertical slots 49 and 50 are formed in the plates 45 and 46 and receive a freely movable upper pin 51 provided with enlargements to prevent displacement. Below the slots 49 and 50 are angular registering slots 52 and 53 which receive a lower pin 51a.

Secured to the bow members 17 or a suitable number of them are brackets 54 to which are pivotally secured links 55 in turn pivotally connected to angle members 56 carried by the damper 57. The damper 57 consists of an inverted V-shaped closure which may be composed of sheet metal and terminate in downwardly extending flanges 58 which loosely telescope the beads 14 and 15 of the plates 12 and 13. Connected to the links 55 or a suitable number of them are levers 59 interconnected at their upper ends by a connecting member or members 60. One of the levers 59 also carries a pulley 61 at its upper end and the damper 57 is provided with an opening 62, adjacent to which is a pulley 63 carried by suitable bracket member 64. The opening 62 is placed at such a position on the damper that it is in all positions at the right of the pulley 63.

Connected to one of the levers 59 as through a

pivoted link 65 is a cable 66 which may be a chain, cord or other flexible element. The cable 66 passes from its point of attachment to the link 65 around the pulleys 47 and 61 and in turn 5 over the pulleys 48 and 63 and extends downwardly to a place conveniently accessible for operation of the ventilator. Pivoted to one of the levers 59 at a point below the pulley 61 is a dog 67 which extends between the plates 45 and 46 10 and between the pins 51 and 51^a. In the upper edge of the dog 67 is a notch 68 which is adapted to cooperate with the upper pin 51 and on the lower edge is formed a notch 69 adapted to engage the lower pin 51^a. It will be noted that the 15 notches 68 and 69 extend angularly in opposite directions and are so positioned that the pins 51 and 51^a could be received therein simultaneously except for the vertical spacing of the slots. 20 In Fig. 2 I have shown the parts in the position they occupy when the damper 57 is in closed position. To open the damper the operator pulls downwardly on the cable 66 whereupon the parts assume the position shown in Fig. 6, the action 25 of the cable on the pulley 63 serving to assist the compound pulley system operating on the lever 59. When the parts have assumed the position of Fig. 6, the lowermost notch 69 in the dog 67 will have engaged against the lower pin 51^a. A further pull on the cable 66, being a part of the 30 same pull which brings the parts to that position and separated into two parts for convenience merely, will cause the lower pin 51^a to ride up the inclination of the slots 52 thereby elevating the dog 67 to such a point that the upper pin 51 will have engaged in the upper notch 68. The cable 66 is now released and the parts held 35 in the position indicated in Fig. 7, that is, the dog 67 being held by the pin 51 against return to its original position and the damper 57 being there- 40 by held in open position as indicated in Fig. 7. At the time the cable is released and the return notch of the dog 67 arrested by engagement of the notch 68 and the pin 51, the lower pin 51^a will drop by gravity to the bottom of the slots 52 45 and 53 as indicated in Fig. 7.

When it is desired to close the damper 57, the operator pulls downwardly on the cable 66 whereupon the dog 67 is released from the pin 51 and by reason of having moved slightly to the right 50 from the position shown in Fig. 7, rides upon the pin 51^a, that surface to the left of the notch 68 being in engagement with said pin 51^a. The cable 66 is now released and the parts returned to the position of Fig. 2. It will thus be seen that 55 upon alternate actuations of the lever 59 by the cable 66, the damper will be moved to and held in open position and released therefrom and allowed to return to closed position.

Referring now to the embodiment shown in 60 Figs. 8 to 12, inclusive, the parts having the same construction as in the previous embodiment will be described and indicated by the same reference numerals while parts of different construction will be indicated by different numerals. The roof 65 sections 10 and 11, the plates 12 and 13, and the bows 17 bear the same relations to each other as in Fig. 1 and are tied together with transverse strips 16 of similar construction. The bows 17 are provided with lower upwardly and slightly 70 outwardly extending projections 70 and 71 which are somewhat longer than corresponding projections 20 and 21. The ridge roll 29 and the supporting members 32 and 33 are of substantially the same construction as in the previous form. 75 The baffles 36 and 37 differ in respect to the an-

choring means provided at the upper and lower edges thereof. The lower edges are provided with a series of outwardly pressed or bent pockets 72 out of which are struck inwardly transverse loops 73 as best seen in Figs. 9, 10, and 11. The extreme lower edges, below the pockets 72 are bent slightly outwardly and engage against the plates 12 and 13, semi-circular notches 74 being provided for escape of water. The upper edges are folded inwardly and backwardly and are em- 10 braced in clamping relation by the terminal portions 34 and 35 of the supporting members 32 and 33. It is to be understood that the upper and lower anchoring means just described may be used in the combinations shown in Figs. 1 and 8 15 and the lower anchoring means of Fig. 8 may be used in connection with the upper anchoring means of Fig. 1 and vice versa.

Secured to the transverse members 16 are upwardly opening channel members 75 to which are 20 pivotally connected downwardly opening channel shaped links 76 which in turn are pivotally connected to the flanges of downwardly opening channel members 77 secured to and carrying the damper 57. Secured to the links 76 are lever 25 plates 78 and 79. An extension 80 is riveted to the plate 78 and carries a pulley 79^a. Secured to one of the transverse members 16 are parallel plates 81 and 82 which are provided with registering vertical slots 83 and registering angular 30 slots 84 between which and between the plates 81 and 82 is received a dog 85 pivotally carried by the lever plate 79 and provided with upper and lower notches 86 and 87 similar to those in the first embodiment. Pins 88 and 89 ride freely in 35 the slots 83 and 84 and operate in the same manner as corresponding parts in the first embodiment of the invention described. A pulley 88 is mounted on one of the transverse strips 16 by means of a suitable bracket 89. A cable 90 is secured at one end to a pin 91 carried by the extension 80 and passes over the pulley 88 and is secured to the lower corner of the lever plate 79, as indicated at 91. The cable 90 passes over a similar pulley 92 carried by a bracket 93 to one 40 or more other levers similar to those 78 and 79, if desirable. It is to be understood that the construction just suggested is not shown in the drawings, the cable 90 being broken off at the lower left hand corner of the lower portion of Fig. 12. 50 The construction suggested is to be used in cases where the ventilator is of great length and may simply amount to a repetition of the structure disclosed in Fig. 12, the broken off portion of the cable 90 being connected to an arm correspond- 55 ing to the arm 80 on a lever corresponding to that 78 but positioned at a considerable distance farther to the left than the drawing extends. A channel member 94 is mounted on any suitably 60 fixed part of the device and carries a pulley 95 and an attaching member 96 to which is secured the end of a cable 97 which passes around the pulley 79^a, the pulley 95 and downwardly to a 65 suitably convenient position for operation.

From the foregoing and the drawings, particu- 65 larly Figs. 8 and 12, it will be apparent that a downward force on the cable 97 will result in rotating the arm 80 and plate 78 in a counter clockwise direction about the pivot carried by the element 75. At the same time the cable 90, being attached to the plate 79 at its lower end, will cause it to rotate in the same direction and to the same extent about the pivot carried by the element 75. This rotation will result in elevating the damper 57 and causing a pivot action be- 70 75

tween its brackets 17 and the pivots at the right hand ends of the plates 18 and 19. The latch element 85 attached to the plate 19 will cooperate with the latch elements 86 and 87 in the manner above described. It will thus be seen that by an operation of the cable 97 the damper 51 will be moved to and held in open position and released and allowed to move to closed position alternately upon successive operations. In the case of both 10 embodiments, one operation of the operating cable will cause the damper to be opened and held in open position and the succeeding operation will release it and allow it to move to closed position.

From the foregoing, it will be clear that I have 15 provided a ventilator which is well adapted for its intended purpose and while I have shown and described the present preferred embodiments, I wish it understood that I am not limited to the details shown but only in accordance with the 20 spirit and scope of the appended claims and prior art.

Having thus described my invention, what I claim is:

1. In combination, longitudinally spaced supporting members mounted above a roof opening, a damper movable toward and from said opening, and means for holding said damper in open position, said last means including spaced links pivotally connecting said damper and a plurality of said members, a lever connected to one of said links, a pair of spaced plates, having formed therein registering, vertical, upper slots and angular, registering, lower slots, pins freely movable in said upper and lower slots, a dog pivoted to said lever and riding between said pins and provided with notches in opposite sides thereof and means for operating said lever to engage and disengage said dog and said pins.

2. In combination, longitudinally spaced supporting members mounted above a roof opening, a damper movable toward and from said opening, and means for holding said damper in open position, said last means including spaced links pivotally connecting said damper and a plurality of said members, a lever connected to one of said links, a pair of spaced plates, having formed therein registering, vertical, upper slots and angular, registering, lower slots, pins freely movable in said upper and lower slots, a dog pivoted to said lever and riding between said pins and provided with notches in opposite sides thereof and means comprising a compound pulley system for operating said lever to engage and disengage said dog and said pins.

3. In combination, longitudinally spaced supporting members mounted above a roof opening, a damper movable toward and from said opening, and means for holding said damper in open position, said last means including spaced links pivotally connecting said damper and a plurality of said members, interconnected levers connect-

ed to said links, a pair of spaced plates, having formed therein registering, vertical, upper slots and angular, registering, lower slots, pins freely movable in said upper and lower slots, a dog pivoted to said levers and riding between said pins and provided with notches in opposite sides thereof and means for operating said levers to engage and disengage said dog and said pins. 5

4. In combination, supporting bows mounted above a roof opening, a ridge roll supported by 10 said bows, baffles carried by said bows at each side of said ridge roll, a damper covering said roof opening, links connecting laterally spaced parts of said damper to a plurality of said bows at laterally spaced points, means for moving said 15 links and automatic means for holding and releasing said links alternately upon successive operations of said moving means.

5. In combination in a device of the character described, supporting means, a damper, links connecting said damper and supporting means, a lever connected to one of said links, a pulley mounted on said supporting means, a cable connected to said lever and passing over said pulley for operating said lever to open and close said damper 25 and latching means for latching said damper in open position and unlatching the same alternately and automatically upon successive actuations of said lever by means of said cable.

6. In combination in a device of the character 30 described, supporting means, a damper, links connecting said damper and supporting means, a lever connected to one of said links, a pulley mounted on said supporting means, a cable connected to said lever and passing over said pulley for operating said lever to open and close said damper 35 and latching means for latching said damper in open position and unlatching the same alternately upon successive actuations of said lever by means of said cable, said latching means including 40 a dog pivoted to said lever, plates carried by said supporting means, upper, registering, substantially vertical slots formed in said plate and lower, registering, angular slots formed therein, pins freely movable in said slots and said dog 45 extending between said pins and provided with notches adapted to engage such pins.

7. In combination in a device of the character described, supporting means, a damper, links connecting said damper and supporting means, a lever connected to one of said links, a pulley mounted on said supporting means, an opening in said damper, a pulley mounted on said damper and overhanging said opening, a cable connected to said lever and passing over said pulleys for operating said lever to open and close said damper 50 and latching means for latching said damper in open position and unlatching the same alternately upon successive actuations of said lever by means of said cable. 55

JAMES H. McDERMINT. 60
